CLAIM

The ornamental design for a port sealer device, as shown and described.

DESCRIPTION

FIG. 1 is a top elevation view of a male port sealer for a port sealer device, shown separately for ease of illustration;

FIG. 2 is a bottom elevation view of the male port sealer for the port sealer device, shown separately for ease of illustration;

FIG. 3 is a top elevation view of a female port sealer for the port sealer device, shown separately for ease of illustration;

FIG. 4 is a bottom elevation view of the female port sealer for the port sealer device, shown separately for ease of illustration;

FIG. 5 is a top perspective view of the port sealer device with the male port sealer coupled to the female port sealer;

FIG. 6 is a side elevation view of the port sealer device with the male port sealer coupled to the female port sealer;

FIG. 7 is a side perspective view of the port sealer device with the male port sealer de-coupled from the female port sealer; and,

FIG. 8 is a bottom perspective view of the port sealer device with the male port sealer coupled to the female port sealer. The broken lines illustrate portions of the port sealer device that form no part of the claimed design.
